UNITED STATES PATENT OFFICE.

DAVID ROBERT YARNALL, OF PHILADELPHIA, PENNSYLVANIA, ASSOCIATE TO
YARNALL-WARING COMPANY, OF PHILADELPHIA, PENNSYLVANIA, A CORP-
ORATION OF PENNSYLVANIA.

WEIR-METER CONSTRUCTION AND INLET REGULATION.

1,159,147.

Specification of Letters Patent.

Patented Nov. 3, 1915.

Application filed May 27, 1913. Serial No. 776,128.

To all whom it may concern:

Be it known that I, DAVID ROBERT YARNALL, a citizen of the United States, residing at 316 Preston street, Philadelphia, in the county of Philadelphia and State of Pennsylvania, have invented a certain new and useful Weir-Meter Construction and Inlet Regulation, of which the following is a specification.

10 The purpose of my invention is to insert a self contained weir measuring mechanism under back pressure or not, as desired, between a pump and a feed water heater, using its catch basin as an equalization pool, to 15 protect against flooding of the weir by water from the catch basin.

Further purposes of my invention are, in connection with the above, to accommodate part of the storage below the weir beneath 20 the receiving or weir chamber, increasing the storage without increasing the floor space required, to reduce the rapidity of the fluctuation of the catch basin water level due to flow of water over the weir and withdrawal of water from the catch basin by the 25 pump and to thus smooth out the curve showing weir operation by reducing the fluctuation in a system where water inlet to the weir tank is controlled by reason of variation of catch basin water level.

Without attempting a full showing of the variant forms in which my invention can be used to great advantage, I have shown several forms thereof which illustrate its 35 flexibility and utility and which I have found to be practical and very useful and which at the same time well disclose the principles involved.

Figure 1 is a vertical longitudinal section, partly in elevation of one form of 40 my invention. Fig. 2 is a section of Fig. 1 upon line 2—2 thereof. Fig. 3 is a fragmentary section of Fig. 1 taken upon line 3—3 thereof. Fig. 4 is a vertical longitudinal section partly in elevation of another 45 form of my invention.

My invention relates to measuring apparatus intended specially for use with feed water heaters. As here claimed it is directed to meter inlet regulation as distinguished from outlet regulation and to the meter rather than combinations with the heater or other anterior reservoir on the one hand or with the pump or other boiler feed on

the other hand. These several other features are claimed in others of my applications.

I prefer to place the meter beyond the heater in the direction of flow of the water measured and control the flow of the water into the meter by the level of the water in the catch basin tank. In one form the pump withdrawal and make-up water supply are both regulated by the catch basin water level.

I have shown the heater 1 as connected by pipe 2, valved at 3, with meter tank 4, having within it three chambers 5, 6 and 7, being the weir or receiving chamber, float chamber and catch basin chamber respectively.

The hand valve 3 may be closed to shut off fluid, herein, for convenience, uniformly treated as water, wholly from the meter, in which case it may be passed directly to the pump 8, through by-pass pipes 9, 10, normally closed by hand valve 11. The pump is connected at 12 with the catch basin chamber, used also as an equalizing pool, from which the water is to be withdrawn and this connection is hand-valved at 13 so that it may be closed when desired. Make-up water for the boiler system is provided by pipe 14 in which is located hand valve 15.

The water from the heater which enters 45 the chamber 5, is in communication through pipe 16, screened at 17, with the float chamber 6 causing the height of the conventional float 18 to correspond with the height of water level 19 and consequently with a 50 certain rate of flow over the weir. This float determines the actuation of recording mechanism in the box 20 by means of rod 21 operating through gland 22, as is more fully shown and described in other applications 55 filed by me. This subject matter is not claimed herein.

The zero point 23 is adjusted to the bottom of the weir opening and may be seen through peep hole 24.

The hand controlled valve 25 operated through gland 26, the vacuum break 27, gage glass 28, 3 pipe overflow 29 and relief valve 30 have been illustrated and described in my copending applications, Serial Nos. 165 687,630 for fluid meter and 170,128 for gravity meter, of which this is, in part, a continuation. They provide for maintenance of

any desired pressure or vacuum conditions within the communicating chambers 5, 6 and 7.

My invention is directed toward the storage of the water overflowing from the weir 5 and the control of the water entering and leaving the system by reason of the height of the water stored. I prefer to make the catch basin proper, *i. e.* the distance between the rear wall 31 and the front tank wall 32 10 quite short, in order to save floor space by reducing the total length of the tank. At the same time I am enabled to get a much larger storage space for the overflow water than would be available from the normal 15 catch basin by utilizing the space beneath the weir chamber as part of the effective catch basin, to form the storage space indicated at 33, providing a large pool of water having its surface not only permissibly be- 20 low the level of the bottom 34 of the weir tank but preferably maintained below that level at some point, as 35, in order to avoid quick changes of surface level and the consequent rapid fluctuation in regulation of 25 the flow of water into and out of the meter.

I provide sufficient catch basin space between the higher level of the water below the weir at which inlet of water is shut off automatically and the level of the bottom of 30 the weir notch at 36 to receive all the flow from the weir chamber above this level 36 after inlet of water to the weir chamber has been stopped, thus insuring against submergence of the weir opening from the catch 35 basin side.

I have stiffened the weir chamber by a transverse partition 37 which is apertured at 38 and is united to the frame of the casting and to the bottom plates 39 by insertion 40 of the plate edge between the flanges 40 of the tank and weir chamber bottom.

I control the influx and outflow of water to and from the weir by the float 41 and the following construction. The rod 42, con- 45 nected with the float at one end, is secured at the other end to an end of a rod 43, which end extends within a pocket 44 forming part of the tank. The rod is bushed at 45 where it emerges from the pocket and is supported 50 there and at any suitable point or points 46 so as to be free to rock slightly with the rise and fall of the float. At any suitable points along the rod I place operating mech- 55 anism for opening and closing valves ac- cording to the movement of this rod; and the particular mechanism which I have illus- trated for this purpose comprises a plurality of levers 47, 48 and 49. The lever 47 is connected by link 50 with lever 51, by which 60 automatic valve 52 is made to open the inlet from the feed water heater, as the level 35 recedes and close it as the level rises. The movement in either direction may be made automatic and the lever may then "cause"

the automatic movement of opening or 65 closing. In any event the valve and connections constitute a controller for the inlet water operated by the float to regulate the height of the water in the catch basin.

The lever 48 is connected to a link 53, 70 having lost motion at 54, the other end of the link being connected with a rod 55 by which automatic valve 56 is opened when the level at 35 has become extremely low. This automatic valve is normally kept closed, 75 even when the pin 57 is not in contact with the upper end 58 of the slot 54.

The lever 49 is connected by link 59 with rod 60 by which the preferably automatic valve 61 is opened as the level of water at 80 35 rises, causing the pump to resume operation. In this case also the pump valve and connections constitute a controller operated by the float to regulate the height of water in the catch basin. The height of 85 level at 35 therefore, by whatever connec- tions, is made to control the normal inlet and outlet of the weir or receiving and catch basin or storage chambers and at an extreme movement to admit make-up water to the 90 system. All of the inlet water is inserted upon the upper side of the weir and is therefore measured.

The connections by which the valves, au- 95 tomatic or not, are operated, are preferably made adjustable, in order to provide not only for proper setting initially, but also for correction by reason of wear and such changes of position as accommodate changed requirements in use. I have shown set 100 screws in the lever arms and couplings in the links for this purpose.

In the form in Fig. 4, I have shown an open feed water heater 63 of conventional type, having doors 64, 65, 66 for access there- 105 to, inlet 67 for steam, normally exhaust steam, and separator 68. The make-up water is here supplied through pipe 69 and is au- tomatically controlled by valve 70, lever 71, link 72, lever 73 and float or other means in- side the heater, so that the quantity of make- up water admitted is regulated by the height of water within the heater. The overflow 110 74 further protects the heater. I have shown a vacuum break at 75 and a so-called 115 free or atmospheric exhaust at 76 which, however, as is well known, is frequently con- trolled to permit or provide for pressure within the heater corresponding to the maximum temperature of feed water which the 120 heater is intended to deliver. This heater, so far as described, differs in no particu- lars from existing heaters and need not be changed in any way for the accommoda- tion of my invention.

I have aimed to illustrate the applica- 125 bility here of regulation of water flowing from an open feed water heater to a weir

meter, whether the latter is maintained at heater pressure or not, where no pump regulation is required or desired and independently of whether the catch basin be extended under the weir chamber or not. As to this subject matter, this application is for certain purposes, a continuation of my co-pending application, Serial Number 642,753, filed August 7, 1911, for combined feed water heater and weir meter.

The connection 77 may be used, if desired, to maintain the weir chamber 78 and communicating float chamber 79 and catch basin chamber 80 at the same pressure as that of the feed water heater, or other means of control of pressure conditions within the meter tank, such as disclosed hereinbefore may be utilized. Any suitable float 81 transmits the record of the rate of flow to the drum 82, by means of suitable mechanism shown within the box 83 and described fully by me in co-pending applications. The float chamber communicates with the weir chamber through pipe 84, valved at 85 and screened at 86. The inlet pipe 87 from the heater is shown as valved at 88 for automatic operation by means of rod 89 acting through packing 90 and impelled by float 81, so that the opening and closing of the valve is controlled by the height of the water level at 92 in the catch basin. The pump 93 draws water from the catch basin through pipe 94.

The water entering through pipe 87 is preferably conducted through a pipe 95 to a point back of the baffle plate at 96 so as not to cause fluctuation of the water level in proximity to the weir opening.

It will be evident that I maintain complete control over inlet water passing from the feed water heater into the meter, that this control is automatic and that it is obtained by reason of the variation in level of the water in the catch basin. The level of water at which the valve is closed preferably provides storage space for all of the water which can then lie in the weir chamber above the level of the weir opening.

Having thus described my invention what I claim as new and desire to secure by Letters Patent is:

1. In a device of the character stated, a weir meter comprising a closed casing containing a weir chamber and a catch basin, the latter being provided with an outlet, a liquid supply conduit entering the weir chamber and constituting the channel for the main liquid supply for the meter, a normally open valve adapted to regulate the flow through the conduit, a float operated by the liquid in the catch basin, and connections operated by the float to reduce the valve opening for inlet flow of liquid from the source of supply as the liquid level in the catch basin rises and to increase the

valve opening for flow of liquid from the source of supply as the liquid level in the catch basin falls.

2. In a device of the character stated, a weir meter casing having a weir chamber 70 and a catch basin, a liquid supply conduit for the weir chamber constituting the main supply therefor, a normally open valve for said conduit where it enters the weir chamber, a float in the catch basin and connections between the float and valve adapted to reduce the valve opening for flow of liquid through the valve, as the height of liquid increases in the catch basin and increase the valve opening for liquid flow, as the height of liquid in the catch basin falls, the valve being so set that it will be closed at such a catch-basin liquid-level as to receive below the level of the weir all the overflow from the weir chamber.

3. In a device of the character stated, a weir meter casing having a weir chamber, a catch basin and a main inlet for liquid admitted to the weir chamber, a normally open valve in the inlet regulating the flow of liquid admitted to the weir chamber and catch basin liquid-controlled means for operating the valve to regulate the amount of liquid admitted to the weir chamber in inverse proportion to the height of catch basin liquid level.

4. In a device of the character stated, a meter casing having therein a weir chamber and a catch basin of which catch basin a portion is located at a lower level than and in front of the weir and a portion is extended beneath the weir chamber, an inlet for the weir, a valve for the inlet, a float within the catch basin and means operated by the float for controlling the inlet valve 105 position by the height of fluid in the catch basin.

5. In a meter of the character stated, a pressure-tight casing having receiving and storage compartments, a relief valve therefor, a float operated by the height of water in the storage compartment of the meter, an intake water connection for the receiving compartment of the meter, a valve in the intake and connections between the float and intake valve to open the intake in inverse proportion to the height of water in the storage compartment.

6. In a device of the character stated, a meter casing having a receiving and measuring compartment and a storage compartment, a return water connection for the measuring compartment, a make-up water connection for the measuring compartment, a valve in each connection, the valve in the make-up water connection being normally closed, a discharge connection from the storage compartment, a float in the storage compartment and connections from the float to the two valves tending to close and open.

- them with differences in height of the water level in the storage compartment.
7. In a device of the character stated, a receiving and measuring compartment, a return water connection therefor, a make-up water connection therefor, a valve in each connection, the valve in the make-up water connection being normally closed, a storage compartment, a discharge connection therefrom, a float in the storage compartment, connections from the float to the two valves tending to close and open them with differences in height of the water level in the storage compartment and a lost motion device whereby the make-up water valve is not opened until the level of the water in the storage compartment becomes low.
8. In a device of the character stated, a meter casing having a weir chamber and a catch basin chamber extended beneath the weir chamber, an inlet for the weir chamber, a valve in the inlet, a float in the catch basin and connections between the float and valve adapted to maintain the level of the water in the catch basin normally below the bottom of the weir chamber.
9. In a device of the character stated, a meter casing having a weir chamber and a catch basin extended within the space beneath the weir chamber, a float in the catch basin, an inlet for the weir chamber, a normally open valve in the inlet and connections between the float and valve adapted to maintain the level of the water normally below that of the bottom of the weir chamber, the proportioning of the catch basin and weir parts being such that there is room in the catch basin for all the water in the weir chamber above the weir at the time that the inlet valve is closed.
10. In a device of the character stated, a
- weir chamber, a catch basin therefor located in front of the weir above and below the level of the bottom of the weir chamber and extending also back of the weir beneath the weir chamber, a source of main liquid supply for the weir chamber, a valve regulating the flow of liquid through this supply, a float in the catch basin, connections between the float and valve, whereby to maintain the catch basin liquid level below the bottom of the weir chamber in normal operation and a register float responsive to the height of liquid level in the weir chamber.
11. In a device of the character stated, a weir-meter having a receiving compartment and a catch basin, a main inlet connection for the receiving compartment, an outlet connection for the catch basin, a normally open valve for regulating the quantity of fluid passing through one of said connections and means set in operation by variation of the fluid level in the catch basin for reducing or increasing the opening of the valve.
12. In a device of the character stated, a weir chamber, a chamber receiving the weir flow, located in front of the weir above and below the level of the bottom of the weir chamber and extended beneath the weir chamber to provide storage thereunder for the water measured, a main inlet connection for the weir chamber, a discharge connection for the chamber below the weir and means closing the inlet connection for regulating the height of water in the chamber above the weir by the level of the water in the chamber below the weir.

DAVID ROBERT YARNALL.
